Inventor.

Ferdinand Imhorst.

UNITED STATES PATENT OFFICE.

FERDINAND IMHORST, OF NEW YORK, N. Y.

IMPROVEMENT IN CHAMBER-POTS.

Specification forming part of Letters Patent No. 124,824, dated March 19, 1872.

To all whom it may concern:

Be it known that I, FERDINAND IMHORST, of the city, county, and State of New York, have invented a new and useful Improvement in Chamber-Pots; and I do hereby declare the following to be a full, clear, and exact description thereof, which will enable those skilled in the art to make and use the same, reference being had to the accompanying drawing forming part of this specification, in which drawing—

Figure 1 represents a vertical central section of this invention. Figs. 2 and 3 are top views thereof with the cover removed.

Similar letters indicate corresponding parts.

This invention consists in forming a chamber-pot, especially at its mouth, of an oval, pear, or egg shape, and arranging upon the upper edge an inwardly-projecting flange in such a manner that when the vessel is suddenly moved, the danger of spilling the contents is materially lessened, the flange preventing their escaping or splashing over.

In the accompanying illustration of this invention, the letter A designates a chamber-pot which is, in this instance, made in the shape of an egg, but which may also be pear or oval shaped, if desired. On the upper edge of this vessel I have formed an inwardly-projecting flange, *a a*, and an outwardly-projecting flange, *b b*. The flange *a a* I consider of great advantage in the construction of a chamber-pot, as, by suddenly moving the vessel the contents thereof are necessarily agitated and brought out of position, and thereby have a tendency to splash over the edge. By forming the inner flange on the upper edge, however, this is obviated, as the contents, if tossed

about, will strike this flange and be arrested and prevented from leaving the vessel. The object of the outwardly-projecting flange *b b* is to form, in combination with the inwardly-projecting flange *a a*, a convenient seat, which shall be wide enough to form a good surface to support the body.

Forming the chamber in an oval or egg shape is of advantage, not only by being thereby better adapted to the human figure, and therefore presenting an "easy" surface to rest upon, but also, by obviating the tendency, which characterizes round-mouthed chambers, to distend the muscles of the lower part of the body and produce the disorder commonly known as piles. Another advantage of this form of mouth in utensils of this description, consists in the facility for emptying, by means of its narrow ends, as the contents can be better directed and controlled than when the mouth of the utensil is circular. The inside flange *a* can terminate or vanish at either or both ends, so as to form a good outlet or passage for emptying the vessel; and in Fig. 2 the flange is thus interrupted or made to vanish at the end opposite the handle *c*.

What I claim as new, and desire to secure by Letters Patent, is—

As a new article of manufacture, an oval, pear, or egg shaped chamber-pot, provided with an inwardly-projecting flange, *a*, upon its upper edge substantially as and for the purpose set forth.

FERDINAND IMHORST.
